UNITED STATES PATENT OFFICE.

HARRY DALITZ, OF CLEVELAND, OHIO, ASSIGNOR TO THE RELIABLE MANUFACTURING COMPANY, OF CLEVELAND, OHIO.

DESIGN FOR A LENS-PLATE.

59,720.

Specification for Design.

Patented Nov. 22, 1921.

Application filed June 29, 1921. Serial No. 481,400. Term of patent 7 years.

To all whom it may concern:

Be it known that I, HARRY DALITZ, a citizen of the United States, residing at Cleveland, in the county of Cuyahoga and State of Ohio, have invented a new, original, and ornamental Design for a Lens-Plate for Signal-Lamps, of which the following is a specification, reference being had to the accompanying drawing, forming part thereof, in which—

The figure is a front elevation of a lens plate for signal lamps, showing my new design.

I claim:

The ornamental design for a lens plate for signal lamps, as shown.

HARRY DALITZ.
